UNITED STATES PATENT OFFICE.

JOHN MONTGOMERY, OF TORONTO, ONTARIO, CANADA.

BOX-CAR DOOR.

1,265,478.

Specification of Letters Patent.

Patented May 7, 1918.

Application filed October 22, 1917. Serial No. 197,823.

To all whom it may concern:

Be it known that I, JOHN MONTGOMERY, (who is a subject of the King of Great Britain,) residing at Toronto, county of York, 5 Province of Ontario, Canada, have invented a certain new and useful Improvement in Box-Car Doors, and declare the following to be a full, clear, and exact description of the same, such as will enable others skilled in 10 the art to which it pertains to make and use the same, reference being had to the accompanying drawings, which form a part of this specification.

My invention relates to box car doors and 15 has for its object the creation of a perfectly tight door suitable for grain and all products that are usually loaded loose in a box car and which ordinarily require that the door shall be supplemented by inside boarding which is usually made of lumber cut to 20 fit and nailed in place and which is usually destroyed when the car is unloaded.

Another object of my invention is to provide a door that will act as usefully in ordinary service as the present storm or outside door and which is especially adapted to be fastened tightly and securely to car posts so that it will not leak. A still further object of my invention is to provide a door 25 which can be liberated from the sealed position with ease whenever it is desired to open the car and one in which warping or 30 springing of the door will not prevent its opening. The door can also be moved to 35 the side of the car in the ordinary manner and be out of the way.

Further details and objects of my invention will be specified in the description thereof and set forth in the claims.

40 In the drawings,—

Figure 1 is a section of the side of a box car showing the door in position preparatory to fastening.

Fig. 2 is a cross-section on the line X—X, 45 of Fig. 1, but with the doors partially swung from the opening preparatory to moving it along the track upon which it runs.

Fig. 3 is a cross-section on the line X—X of Fig. 1, except that it shows the door closed 50 and in a locked position.

Fig. 4 is a vertical section on the line Z—Z, Fig. 1, of a portion of the box of the car showing the upright edge of the door and means for carrying it in locked position.

55 Fig. 5 is a detailed drawing of the appa-

ratus whereby the door is swung inwardly preparatory to locking.

Fig. 6 is a detail of the operating mechanism by which the door is locked.

Similar letters refer to similar parts.

In the drawings, A represents a door, B the side of the car. C is the mechanism for swinging the door in; D is the operative element locking the door. J, J represent the locking means for the side of the door; 60 J² that for the bottom. F is a sub-door or observation door and G is an inlet adapted to receive a spout or other means for emptying the car. H is the track upon which the door is attached and travels with friction 70 wheels upon hangers in the usual manner. This is not a part of my invention and therefore need not be particularly described except so far as same is modified to fit the essential features thereof. One hanger, however, is not attached to the door but is attached to an offset revolving shaft C', one portion of said shaft at C² being journaled in the door and being extended as shown in Fig. 1 as a crank C³ at the bottom for the 80 purpose of rotating the shaft. At the other side of the door at H' the usual hanger friction roller is attached to the door in the usual manner. The track itself is placed at an angle with the car body so that the door 85 as it is slid along the track will pass outside the car body but when closing the edge A' will take the position shown in Fig. 2 close in against the door jamb or post which is preferably rabbeted to form an angle in 90 which the edge of the door shall be firmly clamped as hereinafter described. The opposite edge A², ordinarily outside of the surface of the car body, as shown in Fig. 2, is carried inward to fit in its place by the 95 shafts C², the upper end of which being attached to the hanger as shown in Fig. 5, and drawn in when turned by means of the crank C³ so that the crank is in a vertical plane parallel with the face of the car body 100 as shown in Fig. 1. The edge of the door A² is firmly forced into place in a corresponding rabbet in the door post as shown in Figs. 3 and 5. A rotation of the crank C³ will withdraw the door from the position 105 shown and enable it to be slid along the track in a plane parallel with the surface of the outside of the car. As this particular means of closing in and withdrawing doors from their seats is not new or novel, a more 110

particular description is unnecessary as it forms no part of my invention.

The invention hereof relates to means in combination with closed-in doors of the type described whereby the door is effectually sealed and held firmly in place and yet may readily be withdrawn whenever necessary.

To pass to my invention proper:

Upon each door post are mounted vertical plates J, J' adjacent to the door. The inner edges of the plates are chamfered off so that their action upon the door is that of a wedge forcing the door inward when they are brought into play, as hereinafter described. Each of the plates has preferably diagonal slots K, K through which they are bolted loosely to the door post, as shown in Fig. 1, the heads of the bolts retaining the plates J, J' in position. The plate J' has at the bottom of the door an angular extension J^2 so that it, with the extension is shaped like an L . This is also slidably held at the door sill by means of bolts L, L and diagonal slots K, K so that as the side plate is carried inward from the edge of the door the bottom plate is carried also to the left and upward over the edge of the bottom of the door, the chamfered edges wedging the door into place and covering the crack, if any, between the edge of the door and the door jamb and also that between the bottom of the door and the door sill. The plate J at the left of Fig. 1 only extends from the top to bottom of the door, slidably held to the door posts by diagonal slots K, K and bolts L, L as shown, so that when raised it is forced toward the door and over the crack between the door and the door post, in like manner to that of J' . In order to provide for the simultaneous movement of the plates J, J' and J^2 , I have devised an apparatus which consists of a lever D operating by means of a bellcrank and link M and a horizontal bar N . This bar slides in a horizontal groove and is confined therein. Links P, P connect with the lower part of the plate J^2 and when the apparatus is in open position the links are inclined to the vertical. It is obvious that by raising the lever D the bar N would be moved to the left and the links to a vertical position and force the plates J, J' upward. In forcing them upward the slots K would compel the side bar J to pass to the right and the lower bar J^2 could pass over the edge of the sill and also over the bottom of the door wedging the door firmly in position. In order to close the other edge of the door I have devised a lug Q in an angular position attached to the plate J^2 and working in a mortise carrying two friction rollers R, R . As the plate J^2 is moved to the left and upward it forces the plate J upward and by virtue of the slots K and bolts L it is forced over the door from left to right in the same manner and with the result as hereinbefore

described. The lever D is fastened when the door is closed as in the position shown in dotted lines (Fig. 1), when the fastening may be sealed in the ordinary manner so that the door is completely locked by the sealing 70 of this one lever.

What I claim is:

1. In a box car, the combination of a door frame, a door, a track upon which said door travels, means for forcing the door inwardly into position when closed, side plates attached to the outer surface of said frame and adapted to move inwardly over the joint of the door and frame when the door is forced inward, a bottom plate also adapted 75 to move inwardly over the joint of the door and the sill when the door is forced inward, and means for compelling the side plates to move inwardly simultaneously with the bottom plate moving upwardly, said door being adapted to pass over one of said side plates when in its outward position, substantially as described.

2. In combination with a door frame, a door traveling upon a track to open and close, means for moving the door laterally into a closed position, side plates attached to the outer surface of said frame adapted for covering the crack between the door and the jamb, a bottom plate attached to the 90 outer surface of said frame adapted for closing the crack between the door and the sill, means whereby said side plates are moved inwardly, the bottom plate moved upwardly, and locking means for locking 100 the plates in closed position, substantially as described.

3. In a closure for car doors, the combination of a door, door jambs, and sill, each of said door jambs and sill carrying a movable closure plate attached to its outer surface adapted to be moved into position to cover the adjacent crack when said door is closed and adapted to be withdrawn from over said crack to permit the door to be released from a closed position to an open position, and means for simultaneously actuating said plates.

4. In a closure for car doors, the combination of plates adapted to close the crack 115 between the door and the door posts and sill and to recede from the closed position, with a longitudinally moving bar to actuate said plates, linkages between said bar and the lower plate, whereby the bottom and one 120 of the side plates are operated, and a linkage between the lower plate and the other side plate whereby the longitudinal movement of the bar actuates the plates to open and close them, in substantially the manner described.

5. In a closure for car doors, the combination of a car provided with door posts and sill, a door adapted to open and close the opening of said car, an L-shaped side plate 130

adapted to move diagonally to open and close the crack between the door and door frame and the sill, a second plate adapted to move diagonally to cover the opposite 5 crack of the door, and means for simultaneously operating both plates, substantially as described.

6. In a closure for car doors, the combination of a car provided with door posts and 10 sill, a door adapted to open and close the opening of said car, an L-shaped side plate

adapted to move diagonally to open and close the crack between the door and door frame and the sill, a second plate adapted to move diagonally to cover the opposite vertical crack of the door, and means operating upon the arm of the L-shaped plate to simultaneously operate the plates, substantially as described. 15

In testimony whereof, I sign this specification.

JOHN MONTGOMERY.
